E. M. ZICHY

BABY KIT

Filed March 31, 1926

UNITED STATES PATENT OFFICE.

ELIZABETH M. ZICHY, OF NEW YORK, N. Y.

BABY KIT.

Application filed March 31, 1926. Serial No. 98,694.

My invention relates to baby kits, and more particularly to an article of this character adapted to contain various articles necessary to the comfort of an infant while its 5 custodians are traveling with it.

A baby kit embodying my invention is so constructed as to permit the convenient storage of articles of apparel and food for an infant, with due regard to sanitary conditions and convenience in having access thereto.

In a kit embodying the invention, the construction is not only compact, but permits a quick access to the various articles needed, 15 and serves as a temporary support or shelf for discarded articles of apparel.

While the kit may be made largely of leather or leather substitutes, it contains compartments for nursing bottles and removable 20 containers therefor, which will maintain the food within the bottles at the desired temperature over a considerable length of time.

To make the kit sanitary, the various apparel compartments are not only made of 25 waterproof material, but are detachably connected to the more substantial portions of the kit so as to admit of their being removed when the cleaning or airing of same is required, or when it is desired to substitute 30 other compartments therefor.

The construction of the main casing of the kit is such that it may be supported in a manner to permit it to be opened with one hand, and that a portion thereof will automatically assume the position of a shelf as 35 the kit is opened, thus not only facilitating access to the different containers within the casing, but also serving to support discarded garments.

40 The invention resides primarily in a baby kit embodying therein a casing having two sections foldable in relation to each other, a closure flap upon one of said sections, means whereby said flap may be secured in 45 relation to the other section, means secured to the back of the section carrying said closure flap whereby said casing may be suspended, envelope compartments secured to said sections respectively, and means connected with said sections remote from the 50 point of the fold thereof, whereby when the securing means between said flap and said other section is released said sections will assume a substantially right angular posi-

tion with respect to each other; and in such other novel features of construction and combination of parts, as are hereinafter set forth and described, and more particularly pointed out in the claims hereto appended.

Referring to the drawings,

Fig. 1 is a perspective view of a baby kit embodying my invention; and

Fig. 2 is a vertical section therethrough.

Like letters refer to like parts throughout both of said views.

In the embodiment of the invention shown in the drawings, the baby kit illustrated comprises two sections *a* and *b*, foldable in relation to each other through a wide flexible hinge section *c*.

The section *a* has secured thereto by a similar wide flexible hinge section *d*, a flap *e* adapted to be secured to the section *c* by means of locks such as are commonly used upon brief cases, week end bags, etc., indicated at *f*.

To the back of the section *a* is firmly secured a plurality of spring hooks *g* or other means of suspension of the kit in its entirety either from the rack bar of an automobile seat, the handle or other fittings of a perambulator, or any other desired or convenient object.

Within the section *a*, I provide, substantially centrally thereof, an envelope compartment *h* which may be made of any desired material such as rubberized fabric, the flap *h'* of this compartment and the body thereof, being provided with co-operating snap fasteners *h*². At each corner of said compartment *h* is secured one part of a snap fastener *h*³, the other part of which fastener is secured to the section *a*, thus permitting the convenient removal of this compartment for any desired purpose, as for 90 airing or washing same, or to permit the substitution of a new compartment therefor.

An envelope compartment *i* similar to the compartment *h* and having a flap *i'* and snap fastener *i*² for holding the same closed, 100 is secured to the section *b* by means of snap fasteners *i*³ similar to the snap fasteners *h*³.

The capacity of these envelope compartments *h* and *i* is such as to require a fairly wide spacing of the sections *a* and *b* away from each other when the kit is closed, thus necessitating the wide hinge sections *c* and *d* above referred to. This space between the

sections *a* and *b* when closed, affords ample space for pockets *j* of flexible material secured to, and formed upon the section *a* at opposite sides of the compartment *h*. These 5 pockets are open at the top and have openings *j'* at opposite sides thereof adjacent the bottom of the pocket. They are made of flexible material such as leather or leather substitute, and have a capacity sufficient 10 to receive an ordinary nursing bottle and a heavy fabric envelope *k* therefor, said envelope and the pocket not only forming an adequate protection to the bottle to prevent any likelihood of its breakage, but also preventing 15 a rapid radiation of heat from the contents of the bottle.

The opposite edges of the sections *a* and *b* are connected by means, as the flexible straps *m*, whereby when the securing means *f* between 20 the flap *e* and the section *b* are released, said section will automatically fall away from, and assume a substantially right angular position toward the section *a*, the section *b* extending substantially horizontally so as to form a shelf. The straps *m* each have one end thereof connected to the section *a* adjacent the hinge section *d* and the other end thereof secured adjacent the free 25 edge of the section *b*.

At the fold or hinge, *d*, I also secure an ordinary handle *n*.

When the kit is suspended by means of the hooks *g*, the pockets *j* open upwardly or towards the flap *e* so that the custodian of 30 a child may readily release the lock *f* with one hand while the other hand is occupied, the effect of releasing this lock being to free the section *b* so as to cause the automatic opening of the kit in a manner to permit 35 access to all parts thereof. The connections or straps *m* will limit the opening movement of the section *b* about the hinge section *c* and thus form a shelf having sufficient rigidity to support articles of apparel, 40 bottles or other articles deposited thereon. The use of envelope compartments will also permit the opening of these compartments when one hand only is free, the possibility 45 of thus opening the kit and the different compartments therein with one hand, being highly desirable in an article of this character, and the right-angular positioning of the two sections *a*—*b* of the casing when the 50 kit is opened, is also a matter of great convenience. In removing articles of apparel from the compartment *a* or compartment *h* or *i* one hand only is also necessary, although when storing articles in said compartments, the use of both hands is required.

60 The envelope compartments *h* and *i* may be made of any desired waterproof material, not only for the protection of the casing but for sanitary reasons.

65 Either compartment may be removed from the casing proper, and be readily

cleansed or aired, it being possible to substitute fresh envelope compartments therefor at any time.

The sections *a* and *b*, the hinge sections *c* and *d* and the flap *e* may be composed of 70 leather or leather substitutes and may be made of flexible material throughout, or the two sections *a* and *b* may be suitably reinforced to give greater rigidity thereto.

The hooks *q* when formed of flat metal 75 stock as shown, will increase the rigidity of the section *a*, although other means of suspension may be secured to this section so long as the construction of such means is such that it will not interfere with the free opening and closing of the kit in the manner above described.

Low cost of production of the article is not essential, it being possible to make it of materials of various qualities, the quality 85 of the materials entering into the case being a controlling cost factor.

It is not my intention to limit the invention to the precise details of construction shown in the accompanying drawings, it 90 being apparent that such are capable of considerable variation without departing from the spirit and scope of the invention.

Having described the invention, what I 95 claim as new and desire to have protected by Letters Patent, is:—

1. A baby kit embodying therein a casing having two sections foldable in relation to each other, a closure flap upon one of said sections, means whereby said flap may be secured in relation to the other section, means secured to the back of the section carrying said closure flap whereby said casing may be suspended, said means being positioned below the joinder of said flap with said section, envelope compartments secured to said sections respectively, and means connected with said sections remote from the point of the fold thereof, whereby when the securing means between said flap and said other section is released said sections will assume a substantially right angular position with respect to each other.

2. A baby kit embodying therein a casing having two sections foldable in relation to each other, a closure flap upon one of said sections, means whereby said flap may be secured in relation to the other section, means secured to the back of the section carrying said closure flap whereby said casing may be suspended, said means being positioned below the joinder of said flap with said section, envelope compartments having a closure flap and a snap fastener for holding said flap in the closed position, snap fasteners secured to said compartments and to said sections respectively, whereby said compartments are removably secured to said sections respectively, and means connected with said sections remote from the 130

point of the fold thereof, whereby when the securing means between said flap and said other section is released said sections will assume a substantially right angular position with respect to each other.

3. A baby kit embodying therein a casing having two sections foldable in relation to each other, a closure flap upon one of said sections, means whereby said flap may be secured in relation to the other section, hooks secured to said section having said closure flap, whereby said section may be suspended, said hooks being located at a point below the joinder of the section carrying same and said closure flap, envelope compartments having a closure flap and a

20 snap fastener for holding said flap in the closed position, snap fasteners secured to said compartments and to said sections respectively, whereby said compartments are removably secured to said sections respectively, and flexible straps connected with said sections remote from the point of the fold thereof, whereby when the securing means between said flap and said other section is released said sections will assume a substantially right angular position with respect to each other.

25 In witness whereof I have hereunto affixed my signature, this 29th day of March, 1926.

ELIZABETH M. ZICHY.
